UNITED STATES PATENT OFFICE.

MAHLON HAMLIN, OF CATAWISSA, PENNSYLVANIA.

AXLE-BOX.

SPECIFICATION forming part of Letters Patent No. 358,659, dated March 1, 1887.

Application filed December 20, 1886. Serial No. 221,100. (No model.)

To all whom it may concern:

Be it known that I, MAHLON HAMLIN, a citizen of the United States, residing at Catawissa, in the county of Columbia and State of Pennsylvania, have invented certain new and useful Improvements in Axle-Boxes, of which the following is a specification, reference being had therein to the accompanying drawings.

This invention relates to certain improvements in journal-boxes for that class of cars commonly employed in mines, in which there is necessarily a very limited amount of room for running and operating the cars; and it has for its object to provide for the ready and convenient removal of the car from the axles, when necessary to do so in case of a breakdown or other injury, so as to permit the car to be repaired and put into operation with the least possible delay, thus avoiding the obstruction to the track which would otherwise occur.

In the drawings, Figure 1 represents a side elevation of a portion of a mining-car, showing my improvements applied thereto; Fig. 2, a transverse vertical sectional view of a journal-box and bearing constructed according to my invention. Fig. 3 represents a longitudinal view of the journal-box, showing a portion of the axle; and Fig. 4, a bottom view of the journal-box.

The letter A indicates the truck or lower portion of the car, which is constructed in the usual manner.

B indicates the upper part of the box, which is flat on top, so as to rest firmly against the bottom of the truck or car, to which it is secured by means of the usual bolts, C. The said part B of the box is provided with downwardly-extending sides b, which are provided with longitudinal rounded grooves c, for the reception of the rounded beads d of the lower portion, D, of the box, by which said portion is held in place.

The upper portion of the box is provided with a beveled recess, e, for the reception of a bearing-block, E, constructed of suitable metal, which is curved on its lower face to set over the axle, the block having beveled edges, by means of which it is confined in its seat.

The front of the upper portion of the box

is formed with a flange, F, having a socket, 50 g, for the reception of a pin, h, by means of which the lower part of the box is confined to its seat. The said flange is rounded and beveled on its upper and lower edges, so as to form no sharp angles which would act as 55 lines of breakage, and the downwardly-extending sides are similarly beveled for a like purpose, thus insuring the utmost strength to the box. The said sides are recessed below for the reception of the heads or screw-nuts of the bolts, so that the same will not be exposed to injury.

The inner side of the lower portion of the box is provided with a semi-cylindrical opening, H, through which the journal of the 65 axle passes, and by which it is held in place, and the recess for the bearing-block is provided with stops or abutments i, to prevent any longitudinal movement of the block.

As constructed, it will be perceived that 70 the lower portion of the box, as well as the bearing-block, may be readily removed from their seats, so as to remove the axle or other parts for repair without inconvenience, which obviates the necessity of removing the bolts— 75 a tedious operation, and one which is difficult to perform.

The lower part of the box may be filled with absorbent, to retain lubricating material and distribute it to the axle.

Having thus described my invention, what I claim, and desire to secure by Letters Patent, is—

1. The combination, in an axle or journal box, of the upper portion having curved longitudinal grooves and the lower portion having correspondingly-shaped flanges or beads adapted to fit into said grooves to hold the parts together, substantially as specified.

2. In an axle-box, the combination, with 90 the upper portion, B, provided with beveled recess e and downwardly-extending sides, which have longitudinal grooves c on their inner faces, of the lower portion, D, provided with longitudinal flanges d, adapted to fit the 95 grooves c, and the bearing-block E, adapted to fit the recess e, substantially as described.

3. In an axle-box, the combination, with

the upper stationary portion adapted to be secured to a car and provided with a perforated flange, F, and grooves *c*, of the lower portion, D, constructed substantially as described, and 5 provided with longitudinal flanges *d*, and the securing pin *h*, substantially as herein set forth.

In testimony whereof I affix my signature in presence of witnesses.

MAHLON HAMLIN.
